UNITED STATES PATENT OFFICE.

HARRY ULMER, OF PHILADELPHIA, PENNSYLVANIA, ASSIGNOR TO HARDWICK & MAGEE COMPANY, OF PHILADELPHIA, PENNSYLVANIA, A CORPORATION OF PENNSYLVANIA.

DESIGN FOR A CARPET OR RUG.

40,627.

Specification for Design.

Patented Apr. 12, 1910.

Application filed February 17, 1910. Serial No. 544,522. Term of patent 7 years.

To all whom it may concern:

Be it known that I, HARRY ULMER, a citizen of the United States, residing in Philadelphia, Pennsylvania, have invented a new, original, and ornamental Design for a Carpet or Rug, of which the following is a specification.

The figure in the accompanying drawing represents sufficient of the complete carpet or rug to illustrate my new design, the remainder being simply a repetition of what is shown in the drawing.

1 represents part of the body of the carpet or rug and 2 part of the border of the same.

I claim:

The ornamental design for a carpet or rug, as shown and described.

HARRY ULMER.
